Primary Examiner — Paula Greene(74) *Attorney, Agent, or Firm* — Kristofor L. Storwick**CLAIM**

The ornamental design for a hearing protector housing, as shown and described.

DESCRIPTION

FIG. 1 is a top perspective view showing the new design for a hearing protector housing;

FIG. 2 is a front view thereof;

FIG. 3 is a back view thereof;

FIG. 4 is a top view thereof;

FIG. 5 is a bottom view thereof;

FIG. 6 is a left view thereof; and,

FIG. 7 is a right view thereof.

The broken lines form no part of the claimed design, and any shading is provided to illustrate contour only and is not an indication of texture, gloss, etc.

1 Claim, 2 Drawing Sheets(56)
